UNITED STATES PATENT OFFICE.

DORA S. MILLER, OF LOS ANGELES, CALIFORNIA.

DESIGN FOR AN AUTOMOBILE BODY.

Application filed November 1, 1926. Serial No. 19,555. Term of patent 14 years.

To all whom it may concern:

Be it known that I, DORA S. MILLER, a citizen of the United States of America, residing at Los Angeles, in the county of Los Angeles and State of California, have invented a new, original, and ornamental Design for Automobile Bodies, of which the following is a specification, reference being had to the accompanying drawing, forming part thereof.

Fig. 2 is another side elevation of the other side thereof.

I claim:

The ornamental design for an automobile body, as shown.

DORA S. MILLER.
